MACHINE FOR MEASURING AND INDEXING MATTRESS BORDER STRIPS

Joel G. Strandberg, St. Paul, Minn., assignor to Bechik Products, Inc., St. Paul, Minn., a corporation of Minnesota

Application April 9, 1956, Serial No. 576,849

12 Claims. (Cl. 271—2.5)

My invention relates generally to machines utilized in the manufacture of mattresses and more specifically to measuring and indexing machines for use in preparing mattress border strips prior to assembly thereof to a mattress.

Marginal or border strips for mattresses are generally made with inner and outer fabric walls having a relatively thin layer of padding material therebetween and stitched together. These strips are generally made sufficiently long to provide material for a multiplicity of mattresses, and are shipped or stored in large rolls thereof. Preparatory to being applied to a mattress a strip of predetermined length is drawn from the roll and pierced at selected portions to receive ventilator grommets and handle mounting devices. Inasmuch as mattresses are produced in several sizes requiring border strips of various lengths, care must be exercised in the placement of the various ventilators and handle mounting means so that, when the border strip is sewn to the mattress, the handles and ventilators will be positioned evenly and properly thereon.

My present invention is intended primarily for use as an accessory to combination punch and grommet setting devices of the type disclosed and claimed in the United States Letters Patent No. 2,705,087 issued to Michael Bechik, for the purpose of drawing border strip material through said machine and indexing the same as above indicated.

An important object of my invention is the provision of a mattress border strip measuring device which will automatically draw a predetermined length of border strip from a source of supply and with intermittent movements, whereby accurately spaced portions of said length may be worked upon during intervals between said movements.

Another object of my invention is the provision of a measuring and indexing device as set forth having means for anchoring one end of a border strip and traveling support means movable in one direction to draw said strip from the source of supply, and in the opposite direction to fold the strip after the same has been measured and worked upon.

A still further object of my invention is the provision of a device of the above type having novel means for controlling the intermittent movement of the border strip drawing or feeding means, which control means includes a plurality of groups of control elements, and of mechanism for quickly and easily moving a selected group of control elements into and out of operative positions in said device, whereby to vary the increments of movement of the strip drawing means and to vary the overall measured length of the border strip.

Another object of my invention is the provision of a machine as set forth having a track, a pair of border strip supporting devices on said track, and means for driving one supporting device in border strip feeding and return directions at substantially twice the speed of the other supporting device, whereby a length of border strip is supported at longitudinally spaced portions by both devices

2

and caused to be folded thereover upon return movements of said devices.

Still another object of my invention is the provision of a machine as set forth which is relatively simple and inexpensive to produce, which is highly efficient in operation, and which is rugged in construction and durable in use.

The above and still further highly important objects and advantages of my invention will become apparent from the following detailed specification, appended claims and attached drawings.

Referring to the drawings, which illustrate the invention, and in which like characters indicate like parts throughout the several views:

Fig. 1 is a view in front elevation of a mattress border strip measuring machine built in accordance with my invention, the same being shown in proper working relationship to a punch and grommet setting device, some parts being broken away;

Fig. 2 is a fragmentary view corresponding to a portion of Fig. 1 but showing a different position of some of the parts;

Fig. 3 is an enlarged fragmentary view in plan as seen from the line 3—3 of Fig. 1, some parts being broken away and some parts being shown in section;

Fig. 4 is a fragmentary vertical section taken substantially on the line 4—4 of Fig. 3, some parts being broken away;

Fig. 5 is a transverse section taken substantially on the line 5—5 of Fig. 4;

Fig. 6 is an enlarged fragmentary view partly in plan and partly in section as seen substantially from the line 6—6 of Fig. 1;

Fig. 7 is a fragmentary view partly in front elevation and partly in section as seen from the line 7—7 of Fig. 6;

Fig. 8 is a fragmentary view partly in end elevation and partly in section taken substantially on the line 8—8 of Fig. 7;

Fig. 9 is a fragmentary view partly in plan and partly in section taken substantially on the line 9—9 of Fig. 8, some parts being broken away;

Figs. 10 and 11 are views corresponding to Fig. 9 but showing different positions of some of the parts; and

Fig. 12 is an enlarged fragmentary detail in section taken substantially on the line 12—12 of Fig. 1.

As above indicated, the device of the instant invention is adapted for use as an accessory to machines for punching holes in mattress border strips and inserting grommets in said holes for the purpose of ventilating the interior of the mattress and for supporting opposite end portions of mattress handles. Such a machine is fully disclosed in the Bechik patent, above identified, and need not be herein described in detail. The machine is indicated by the reference character A and is adapted to operate on a border strip, indicated at B, which may be assumed to be taken from a suitable source of supply such as a relatively large roll thereof, not shown.

In the preferred embodiment of my invention illustrated, the numeral 1 indicates in its entirety a frame structure including an elongated horizontally disposed bridge 2 comprising a plate-like front wall element 3 and an elongated rear channel-shaped element 4. Upright end frames 5 and 6 support opposite ends of the bridge 2 in upwardly spaced relation to the ground or floor, indicated at X. An elongated supporting rail or track 7 extends longitudinally within the bridge 2, and is supported at its opposite end portions by supporting arms 8 extending rearwardly therefrom to the inner surface of the channel member 4 and bolted or otherwise rigidly secured thereto. Mounted for longitudinal traveling movements on the track 7 is a carriage 9 having upper and lower track engaging flanged rollers 10 and 11 respectively journaled thereto. Bolted or otherwise rigidly secured to the car-

riage 9 is a bracket 12 which extends forwardly below the lower edge of the front plate 3 and upwardly to provide means for mounting a mattress border strip engaging and supporting pulley element 13. The pulley element 13 is journaled on a shaft 14 that extends forwardly from the upper end of the bracket 12. A second carriage 15 is likewise mounted on the rail or track 7 for longitudinal traveling movements thereon between the carriage 9 and the end of the track 7 adjacent the end frame 5. The second carriage 15, like the carriage 9, is provided with track engaging flanged rollers 16 by means of which the carriage 15 travels on the track 7. Preferably, the carriage 15 like the carriage 9 is provided with a lower pair of track engaging rollers not shown. A bracket element 17 extends forwardly from the bottom of the carriage 15 and upwardly in front of the front plate 3 and has rigidly secured to its upper end a mattress border strip supporting shaft or pin 18 which extends forwardly therefrom at a level substantially that of the pulley 13.

Mounted on the end of the bridge 2 overlying the end frame 5, is a strip receiving clamp 19 having a relatively stationary upper jaw 20 and a relatively movable jaw 21; that is: provided with a depending leg 22 slidably mounted in a bearing plate or the like 23 secured to the adjacent end of the front plate 3. The lower end of the leg 22 is pivotally secured to one end of a lever 24 pivotally secured intermediate its ends to the front plate 3, and to the other end of which is pivotally connected the upper end of a rigid link 25, the lower end of which is connected to a foot-operated lever 26 by means of which the clamp 19 may be opened or closed. As shown in Figs. 1 and 2, the border strip supporting brackets 12 and 17 are adapted to be moved by their respective carriages 9 and 15 in a direction from the end frame 5 toward the end frame 6 with an intermittent movement whereby to draw and feed the border strip B through the machine A. The free end of the border strip B is passed over the clamp 19, the supporting shaft or pin 18 and the supporting pulley 13. The free end portion of the border strip B is then passed between the supporting pin 18 and the overlying portion of the strip B and clamped between the jaws 20 and 21 of the clamp 19. It will be noted that the supporting pin 18 is substantially centrally located between the supporting pulley 13 and the clamp 19 when the same are in their starting and return positions of Fig. 2. This relationship between the pulley 13 and supporting pin 18 is maintained throughout the feeding travel of the carriages 9 and 15 on the track 7 and during return travel thereof by means hereinafter to be described. For the purpose of the present example, the carriages 9 and 15, during feeding movement thereof from the left to the right with respect to Fig. 1 travel intermittently and in predetermined increments to several operating stations as shown by dotted lines in Fig. 1. The several stations assumed by the bracket 12 and pulley 13 are designated P-1, P-2, P-3, P-4 and P-5. The corresponding stations assumed by the bracket 17 and its supporting pin 18 are indicated at S-1, S-2, S-3, S-4 and S-5. Thus it will be seen that in all positions of the bracket 12 and roller 13, the bracket 17 and supporting pin 18 are disposed substantially centrally between the bracket 12 and the clamp 19 whereby to evenly support the border strip B between the clamp 19 and the pulley 13. It will be further noted that for a given movement of the pulley 13 away from the clamp 19, a length of border strip substantially twice the length of said given travel is drawn through the machine A.

For the purpose of imparting traveling movements to the carriages 9 and 15 I provide a drive shaft 27 journaled in bearings 28 mounted on supporting brackets 29 that are suitably mounted in the end of the bridge 2 above the supporting leg or end frame 5. A sprocket wheel 30 is pinned or otherwise rigidly mounted on the drive shaft 27 for common rotation therewith and has running thereover a drive chain 31 which has one end secured to one

of a pair of anchoring blocks 32 on the carriage 9, by means of an anchoring screw or the like 33. The drive chain 31 runs over a second sprocket wheel 34 mounted fast on a shaft 35 that is journaled in spaced bearings 36 at the opposite end of the bridge 2 above the supporting leg or end frame 6. The bearings 36 are mounted on a supporting bracket 37 bolted or otherwise rigidly secured to the adjacent end portion of the bridge member 4. The opposite end of the drive chain 31 extends from the sprocket wheel 34 toward the carriage 9 and is rigidly secured to the adjacent anchoring block 32 by means of a second anchoring bolt 38 or the like substantially identical to the anchoring bolt 33. The second carriage 15 is provided with an anchoring block 39 to the opposite sides of which are anchored the opposite ends of a drive chain 40, by means of anchoring screws 41. The drive chain 40 runs over a sprocket wheel 42 mounted on the shaft 35 and a drive sprocket wheel 43 pinned or otherwise rigidly secured to the drive shaft 27. With reference to Figs. 3-7 it will be seen that the sprocket wheels 30 and 34, which are identical in size, are of twice the diameter of the sprocket wheels 42 and 43 which latter are also identical in size. This differential in sprocket wheel size causes the drive chain 31 to be moved substantially twice as fast as the drive chain 40, the speed of rotation of the drive sprocket wheels 39 and 43 being identical. Thus, at any given position of the carriage 9 and parts carried thereby, the carriage 15 and parts carried thereby will always be positioned substantially centrally between the carriage 9 and the end of the border strip B secured in the clamp 19. The drive shaft 27 is driven by a motor 44 suitably mounted in the end frame 5 by suitable transmission mechanism comprising a conventional speed reduction transmission not shown but contained within a housing 45, an endless belt 46 running over a pulley 47 on the drive shaft of the motor 44 and a second pulley 48 on the input shaft 49 of the transmission mechanism. A sprocket wheel 50 is mounted on the output shaft 51 of the transmission mechanism, and has running thereover an endless link chain 52 that runs over another sprocket wheel 53 pinned or otherwise rigidly mounted on the drive shaft 27.

Means for controlling the drive motor 44 to impart feeding movement to the carriage 9 toward the end frame 6, and return movement thereto toward the end frame member 5 includes a reversing switch 54 and cooperating elements, now to be described. The reversing switch 54 is conventional in nature and it is believed not necessary that the same be described in detail. However, the reversing switch 54 is shown as being provided with an operating arm 55, shown in Fig. 7 in a neutral position, from whence the same may be swung in an upward direction to cause the motor 44 to impart feeding movements to the carriages 9 and 15, and in a downward direction to cause return movements to be imparted to the carriages 9 and 15. A bell crank 56 is mounted for swinging movements on a stub shaft 57 that is mounted in suitable bearings 57' in the head end of the bridge 2 above the end frame member 5, and has one arm 58 connected to the switch operating arm 55 by means of a rigid link 59, see Fig. 7. The other arm 60 of the bell crank 56 extends in a generally upward direction and has its upper free end contained in a downwardly opening notch 61 in a relatively short arm 62 of a shift crank 63. The shift crank 63 is journaled on a shaft 64 rigidly secured at its opposite ends to the front plate 3 and rear channel 4 of the bridge 2 above the end frame or leg 5. A pair of tubular spacer elements 65 and 66 properly locate the shift crank 63 between the front wall 2 and the rear channel 4. The shift crank 63 is provided with a relatively long depending arm 67 to the lower end of which is rigidly secured a rearwardly projecting pin 68 that has its free rear end received in a downwardly opening notch or channel 69 of a block-like collar 70 rigidly secured to a control element or shaft 71. The

shaft 71 extends longitudinally within the bridge 2 and is mounted at one end portion in an end wall 72 of the bridge 2 above the end frame 5 for rotary and axial sliding movements therein. The opposite end of the shaft 71 is supported for rotary and axial sliding movements in a supporting block or the like 73 that is mounted on the supporting arm 8, see Figs. 3 and 4. Rigidly mounted on the control shaft 71 are a plurality of abutment elements or the like 74, each having axially projecting stop fingers 75, and defining cam acting bottom surfaces 76. Each abutment element 74 is provided with a key 77 which is adapted to be seated in a selected one of a plurality of circumferentially spaced axially extending keyways 78 in the control shaft 71. As indicated in Fig. 12, the abutment elements 74 are arranged in circumferentially spaced groups of axially spaced abutment elements for a purpose which will hereinafter be described. A bevel gear 79 is mounted on the end portion of a shaft 81 for axial sliding movements with respect thereto but for common rotation therewith adjacent the end wall 72. A cooperating bevel gear 80 is rigidly secured to the lower end of a vertically disposed shaft 81 journaled in a bearing bracket 82 that is anchored to the wall 72. The shaft 81 extends upwardly through a top wall element 83 of the adjacent end of the bridge structure 2, and terminates in an adjustment wheel or handle 84 by means of which the shaft 71 may be rotated.

A rockshaft 85 extends longitudinally within the bridge 2 and is journaled at its opposite ends in bearings 86 at opposite ends of the bridge structure. With reference to Figs. 5 and 12, it will be seen that the rockshaft 85 extends freely through an aperture 87 in the carriage 15 and through similar apertures 88 in the anchoring block 32 of the carriage 9. Rigidly secured to the rockshaft 85 between the anchoring blocks 32 in the carriage 9 is a stop dog 89 which extends generally rearwardly from the rockshaft 85 and which is movable about the axis of the rockshaft 85 toward and away from an operative position in registration with selected ones of the abutment elements 74 on the control shaft 71. With reference particularly to Fig. 5, it will be seen that the stop dog 89 is yieldingly urged toward its operative position by a coil tension spring 90 secured at its upper end to an anchoring pin 91 extending forwardly from the adjacent end of the stop dog 89, and at its lower end to the bottom portion of the carriage 9. One end of the rockshaft 85 extends outwardly beyond the wall element 72, and has secured thereto an operating handle 92 by means of which the operator may rock the shaft 85 in a direction to move the stop dog out of registration with a given abutment element 74 against the bias of the spring 90. Predetermined rotary movement of the control shaft 71 by the adjustment wheel or handle 84 will position a selected group of abutment elements 74 in the path of travel of the stop dog 89. The several abutment elements of one group, being axially spaced from those of another group, will stop feeding movements of the carriages 9 and 15 at different longitudinally spaced points than those of another group. With the above described arrangement, border strips having different dimensions between the groups of holes and grommets therein may be obtained without the necessity of shifting the abutment elements 74 longitudinally on the control shaft 71. When it is desired to so change the dimensions between sets of holes or grommets of a border strip, it is merely necessary that the operator turn the adjustment knob or handle 84 in a direction to bring the selected group of abutment elements 74 into the path of travel of the stop dog 89. For the purpose of controlling the extreme limits of feeding and return movement of the carriage 9, I provide stop collars 93 and 94 adjustably secured on the shaft 71, the former adjacent the end frame 6 and the latter adjacent the opposite end frame 5. It will be noted that, during

feeding movement of the carriages 9 and 15, the stop dog 89 moves into abutting engagement with the adjacent end of the stop finger 75 of one of the abutment elements 74 lying in the path of travel of the stop dog 89. When this occurs, the control shaft 71 will be moved in a direction from the left to the right with respect to Fig. 7, causing the shift crank 63 to swing the bell crank 56 in a direction to move the switch operating arm 55 to its neutral position to stop the motor 44. During return movements of the carriage 9, the stop dog 89 will engage the cam acting surfaces 76 of successive abutment elements 74 and be cammed downwardly thereby so that the carriage 9 will continue its return movement, without moving the central shaft 71, until the stop dog 89 engages the stop collar 94, whereby movement is then imparted to the control shaft 71 in a direction to stop the motor 44.

The control mechanism of my invention includes an actuator comprising a shifter fork 95 pivotally secured to the relatively short arm 62 of the shifting crank 63, by a pivot pin 96. The shifter fork 95 is provided with a stem or shank 97 that projects upwardly through an opening 98 in the top plate or wall element 83, and through an opening 99 in a cover element 100 mounted on the top plate 83. It will be noted by reference to Figs. 7 and 8 that the axes of the pivot pin 96 and the mounting shaft 64 are at right angles to each other, whereby the stem 97 may be moved in an arc about the center of the shaft 64 as well as in an arc about the axis of the pivot pin 96. The opening 99 is formed by a pair of slots 101 and 102 that extend longitudinally with respect to the machine and which are longitudinally and laterally offset from each other. The adjacent ends of the slots 101 and 102 are connected as indicated at 103 to define a neutral station for the stem 97. Said stem 97 is movable about the axis of the pivot pin 96 from an inoperative position at the neutral station 103 selectively to a forward action zone defined by the slot 101 or a reverse action zone defined by the slot 102. The actuator stem 97 is shown in Fig. 9 as being positioned at the neutral station 103. When the actuator stem 97 is shifted to the forward action zone in the slot 101, it is movable between an operative forward position, as shown in Fig. 10, at the end 104 of the slot 101, and an idle position at the end 105 of the slot 101. Likewise, when the actuator stem 97 is shifted from its neutral station 103 to the reverse action zone defined by the slot 102, the same is movable therein between an operative position indicated in Fig. 11 at the end 106 of the slot 102, and an idle position at the inner end 107 of the slot 102. It will be noted that, when the actuator stem 97 is shifted from its neutral position to either of the idle positions in the slots 101 or 102, that such shifting is made independently of the shift crank 63 and parts connected therewith. However, movement of the actuator stem 97 in either action zone between the idle and operative positions thereof, causes the shift crank to be moved in directions to energize the motor 44 for operation in either a forward or return direction. The actuator stem 97 extends upwardly through a central aperture 108 in a plate-like actuator element 109 slidably resting on the top wall element 83 beneath the cover element 100. The opposite side edges of the actuator element 109 are notched to provide laterally spaced surface or edge portions 110 and 111 that are engageable respectively with fulcrum acting pins 112 and 113 projecting upwardly from laterally spaced portions of the top wall element 83 on opposite sides of the actuator element 109. A pair of coil tension springs 114 and 115 extend generally longitudinally of the machine adjacent opposite sides of the actuator element 109, each thereof having one end anchored to an opposite end portion of the plate-like element 109 as indicated at 116 and 117 respectively. The opposite ends of the springs 114 and 115 are anchored to suitable anchoring pins 118 and 119 projecting upwardly from the plate-like element 83. With reference to Figs. 9-11, it will be seen that, when

the actuator element 109 is in its neutral position of Fig. 9, the actuator stem 97 is positioned at the neutral station 103, and the fulcrum-acting pins 112 and 113 each engage a respective surface portion 110 and 111 of the plate-like actuator element 109. At this time, both of the springs 114 and 115 are exerting their yielding bias against the actuator element 109 to urge the same toward engagement of the surface portions 110 and 111 with their respective fulcrum-acting pins 112 and 113. With reference to Fig. 10 it will be seen that when the actuator stem 97 is manually shifted toward the forward action zone defined by the slot 101, the surface portion 111 moves laterally out of engagement with its cooperating fulcrum acting pin 113, the spring 114 moves into substantially dead center relationship with respect to the fulcrum pin 112, and the spring 115 causes the actuator element 109 and stem 97 to be moved to their operative position in the forward action zone, the actuator element 109 swinging about the fulcrum pin 112. This movement is transferred to the control shaft 71 through the shift crank 63, and to the reversing switch 54 through the bell crank 56 and link 59, whereby to energize the motor and cause the same to drive the carriages 9 and 15 in a border strip drawing or feeding direction toward the end frame 6. The motor continues to operate until the carriages 9 and 15 reach their position P2 and S2 respectively of Fig. 1. At this point the stop dog 89 engages the adjacent end of the finger 75 of the first abutment element 74 and causes the control shaft 71 to be moved in the same direction as the carriage. This movement of the control shaft 71 causes the shift crank 63 to swing in a direction to move the actuator stem 97 and the actuator element 109 to the end 105 of the slot 101 wherein the actuator element is in its forward idle position. As above indicated this movement of the actuator stem 97 and actuator element 109 to their idle position in the forward action zone also causes the reversing switch 54 to be positioned at neutral thus shutting off the motor 44. Assuming that a border strip B has been attached to the clamp 19 in the manner above described and the machine A has performed a hole punching and grommet inserting operation on the border strip B while the carriage 9 and 15 are stationed at P1 and S1 of Fig. 1, the border strip is now in a position to be again operated upon by the machine A. After the second group of holes have been punched and grommets installed in the border strip B, the operator manipulates the handle 92 to rock the shaft 85 in a direction to swing the stop dog 89 out of engagement with the adjacent abutment element 74. The spring 115 then moves the actuator stem 97 and actuator element 109 to their operative position of Fig. 10, and swings the shift crank in a direction to cause the motor 44 to be reenergized and to move the control shaft 71 in the direction of the end frame 5. Reenergization of the motor 44 causes the carriages 9 and 10 to advance to their respective positions P3 and S3, whereupon the stop dog 87 engages a subsequent abutment element 74 to cause deenergization of the motor 44 and repositioning of the actuator stem 97 and actuator element 109 at the idle position in the forward action zone. At this point the machine A is again operated after which the handle 92 is manipulated to cause the border strip B to be drawn or fed by the carriage 9 until the carriages 9 and 15 reach their positions P4 and S4 of Fig. 1. The border strip B is again operated on by the machine A and the carriages 9 and 15 caused to be moved to their extreme positions P5 and S5 of Fig. 1, at which time the stop dog 89 engages the stop collar 93. The stop collar 93 is of a size to prevent the stop dog 89 from being moved downwardly out of engagement therewith, and positively limits further feeding movement of the carriages 9 and 15. At this point the operator manually shifts the actuator stem 97 and actuator element 109 from their idle positions in the forward action zone to the reverse action zone defined by the slot 102. This movement causes the

spring 115 to be moved into substantially dead center relationship with the fulcrum pin 113 and causes the spring 114 to become operative to move the actuator stem 97 and actuator element 109 toward their operative positions in the reverse action zone. It will be noted that shifting the actuator stem 97 from the slot 101 to the slot 102 causes the actuator element 109 to be disengaged from the fulcrum pin 112 and the surface position 111 thereof to operatively engage the fulcrum pin 113. This movement of the actuator stem and actuator element is transferred to the switch operating arm 55 and the same is moved in a direction to cause the motor to move the carriages 9 and 15 toward the end frame member 5 until the carriages reach their positions P1 and S1 of Fig. 1. As above noted, during this return movement of the carriages 9 and 15 the stop dog 89 successively engages the cam-acting surface 76 of each abutment element 74 and is cammed downwardly thereby so that the stop dog moves past the abutment elements 74 without causing stoppage of the motor 44 during its return operation. When the carriage 9 reaches its position P1 of Fig. 1, the stop dog 89 engages the stop collar 94 and moves the same in a direction to cause the actuator stem 97 and actuator element 109 to be moved to their idle position in the reverse action zone. It will be noted that, during the return movement of the carriages 9 and 15, the double length of border strip B supported by the roller 13 and supporting stem 18 becomes draped thereover as shown in Fig. 2. After the carriages have arrived at their positions P1 and S1, the border strip is then severed from the roll thereof and at a point to make same of the proper length. Preferably, this is accomplished by a conventional cutter 120 comprising relatively movable and stationary blades 121 and 122 respectively. As shown in Figs. 1 and 2, the cutter 120 is mounted on the end of the bridge 2 overlying the end frame 5. After the length of border strip has been severed, the clamp 20 is released and the finished border strip removed therefrom and from the pulley 13 and supporting stem 18. It will be noted by reference to Fig. 2 that the border strip B, being draped over the pulley 13 and stem 18, the same is very easily removed therefrom and need not be further folded for transportation to a place where the ends of the border strip are sewn together.

While I have shown and described a commercial embodiment of my novel border strip measuring machine, it will be understood that the same is capable of modification without departure from the spirit and scope of the invention as defined in the claims.

What I claim is:

1. In a device of the class described, a supporting structure, an elongated track on said supporting structure, a carriage mounted on said track for movements longitudinally thereof, border strip engaging and supporting means on said carriage, drive means including a motor for imparting movement to said carriage on said track in a direction to transport said border strip, and control mechanism for said drive means, said control mechanism comprising a control member extending longitudinally of said track and shiftable with respect thereto, a plurality of longitudinally spaced abutment elements on said control member, a stop dog mounted for common traveling movements with and for independent movements into and out of registration with said abutment elements, an actuator mounted in said supporting structure for shifting movements in opposite directions in one plane between a neutral station and an action zone and movable in opposite directions in said zone and in another plane between an operative drive position and an idle position, linkage connecting said actuator to said control member, engagement of one of said abutment elements by said stop dog during traveling movements of said carriage in one direction imparting limited movement to said control member to cause said actuator to be moved from its operative position to its idle position to render said drive means in-

operative, and means for moving said actuator from its idle position to its operative drive position upon movement of said stop dog out of engagement with said one of the abutment elements whereby said carriage will be caused to resume travel toward a succeeding abutment element.

2. The structure defined in claim 1 in further combination with yielding means urging said stop dog toward registration with said abutment elements, and means adjacent one end of the track for moving said stop dog out of registration of and engagement with said abutment elements against bias of said yielding means.

3. The structure defined in claim 1 in which said means for moving the actuator to its operative drive position comprises a spring yieldingly urging said actuator toward its operative position in said action zone, said control element being moved by engagement of said stop dog with one of said abutment elements against bias of said spring operating through said linkage.

4. In a device of the class described, a supporting structure, an elongated track on said supporting structure, a carriage mounted on said track for movements longitudinally thereof, border strip engaging and supporting means on said carriage, drive means including a motor for imparting movement to said carriage on said track in a direction to transport said border strip, and control mechanism for said drive means, said control mechanism comprising a control member extending longitudinally of said track and shiftable longitudinally thereof, a plurality of longitudinally spaced abutment elements on said control member, a stop dog mounted on said carriage for common traveling movements therewith and for independent movements into and out of registration with said abutment elements, an actuator mounted in said supporting structure for shifting movements in opposite directions in a plane extending generally transversely of said track between a neutral station and an action zone and movable in opposite directions in said zone between an operative drive position and an idle position and in a plane extending generally longitudinally of said track, linkage connecting said actuator to said control member, engagement of one of said abutment elements by said stop dog during traveling movements of said carriage in one direction imparting limited movement to said control member to cause said actuator to be moved from its operative position to its idle position to render said drive means inoperative, and means for moving said actuator to its operative drive position upon movement of said stop dog out of engagement with said one of the abutment elements whereby said carriage will be caused to resume travel toward a succeeding abutment element.

5. In a device of the class described, a supporting structure, an elongated track on said supporting structure, means adjacent one end of said track for releasably anchoring one end of an elongated mattress border strip, a carriage mounted on said track for movements longitudinally thereof, a pulley on said carriage adapted to be partially encompassed by a portion of said border strip passed therearound, whereby movement of said carriage from one end of the track to the other end thereof will cause a length of said border strip substantially equal to double the length of travel of said carriage to be drawn by said carriage from a source of supply of said strip, drive means including a motor for imparting movement to said carriage on said track in a border strip drawing direction, and control mechanism for said drive means, said control mechanism comprising a control member extending longitudinally of said track and shiftable with respect thereto, a plurality of longitudinally spaced abutment elements on said control member, a stop dog mounted on said carriage for common traveling movements therewith and for independent movements into and out of registration with said abutment elements, an actuator mounted in said supporting structure for shifting movements in opposite directions in one plane between

a neutral station and an action zone and movable in opposite directions in another plane in said zone between an operative drive position and an idle position, linkage connecting said actuator to said control member, engagement of one of said abutment elements by said stop dog during traveling movements of said carriage in one direction imparting limited movement to said control member to cause said actuator to be moved from its operative position to its idle position to render said drive means inoperative, and means for moving said actuator to its operative drive position upon movement of said stop dog out of engagement with said one of the abutment elements whereby said carriage will be caused to resume travel toward a succeeding abutment element.

15 6. The structure defined in claim 5 in further combination with a second carriage mounted on said track between said first-mentioned carriage and said one end of the track, a border strip supporting element on said second carriage, and mechanism including said drive means 20 for moving said second carriage simultaneously with and in the same direction as said first-mentioned carriage and at substantially one-half the speed of said first-mentioned carriage, whereby said border strip will be supported at all times intermediate said pulley and said border strip 25 anchoring means.

7. In a device of the class described, a supporting structure, an elongated track on said supporting structure, a carriage mounted on said track for movements longitudinally thereof, border strip engaging and supporting means on said carriage, drive means including a motor for imparting movement to said carriage selectively in opposite directions on said track, and control mechanism for said drive means, said control mechanism comprising a control member extending longitudinally of said 30 track and shiftable with respect thereto, a plurality of longitudinally spaced abutment elements on said control member, a stop dog mounted for common traveling movements with said carriage and for independent movements transversely thereof into and out of registration with 35 said abutment elements, an actuator mounted in said supporting structure for shifting movements selectively between an intermediate neutral station and forward and reverse action zones, said actuator being movable in opposite directions in each of said action zones, when shifted 40 thereto, between operative drive positions and idle positions, linkage connecting said actuator to said control member, traveling movements of said carriage in either a forward or reverse direction being initiated by said actuator from its neutral station to a respective one of 45 said action zones, engagement of one of said abutment elements by said stop dog during traveling movements of said carriage in a forward direction imparting limited movement to said control member to cause said actuator to be moved from its operative position to its idle position 50 in said forward action zone to render said drive means inoperative, and means for moving said actuator from its idle position to its operative drive position in said forward action zone upon movement of said stop dog out of engagement with said one of the abutment 55 elements whereby said carriage will be caused to resume travel toward a succeeding abutment element.

8. The structure defined in claim 1 in which said control member comprises a shaft mounted for rotary and longitudinal sliding movements in said frame structure, 60 and in which said abutment elements are arranged in circumferentially spaced groups on said shaft, and in further combination with means for imparting rotation to said shaft to position a selected group of said abutment elements to be successively engaged by said stop dog, the abutment elements of one group being spaced from those of the other groups thereof longitudinally of said shaft.

9. The structure defined in claim 1 in further combination with means for moving said stop dog out of engagement with said abutment elements, said means com-

11

prising a rockshaft journaled in said frame structure and extending through said carriage parallel to said track, said stop dog being carried by said rockshaft for common rocking movements therewith into and out of registration with said abutment elements and axially slidable on said shaft; and an operating handle on one end of said shaft for imparting rocking movement thereto in a direction to move said stop dog out of engagement with said abutment elements, and in further combination with yielding means urging said latch dog toward registration with said abutment elements.

10. In a device of the class described, a supporting structure, an elongated track on said supporting structure, a carriage mounted on said track for movements longitudinally thereof, border strip engaging and supporting means on said carriage, drive means including a motor for imparting movement to said carriage selectively in opposite directions on said track to transport said border strip, and control mechanism for said drive means, said control mechanism comprising a control member extending longitudinally of said track and shiftable with respect thereto, a plurality of longitudinally spaced abutment elements on said control member, a stop dog mounted for common traveling movements with said carriage and for independent movements transversely thereof into and out of registration with said abutment elements, an actuator element mounted in said frame structure for shifting movements selectively between an intermediate neutral station and forward and reverse action zones and movable in opposite directions in each of said action zones between operative drive positions and idle positions, said frame defining a wall element adjacent said actuator element, one of said last-mentioned elements having a laterally spaced pair of fulcrum members thereon, the other of said last-mentioned elements defining spaced surface portions each engageable with a different one of said fulcrum members for sliding and swinging movements relative to their respective fulcrum members, each of said fulcrum members being engaged by a cooperating one of said surface portions to prevent movement of said actuator element toward either operative drive position when said actuator element is positioned at said neutral station, movement of said actuator element to either one of said action zones causing disengagement of one of said fulcrum members by its respective one of said surface portions to permit sliding and swinging movements of said actuator element in one of said action zones about the other of said fulcrum members, linkage connecting said actuator element to said control member, traveling movements of said carriage in either a forward or reverse direction being initiated by shifting of said actuator from its neutral station to the operative drive position in a respective one of said action zones, engagement of one of said abutment elements by said stop dog during traveling movements of said carriage in a forward direction imparting limited movement to said control member to cause said actuator element to be moved from its operative position to its idle position in said forward action zone to render said drive means inoperative, and means for moving said actuator from its idle position to its operative drive position upon movement of said stop dog out of engagement with said one of the abutment elements whereby said carriage will be caused to resume travel toward a succeeding abutment element.

11. The structure defined in claim 10 in which said means for moving said actuator element from its idle po-

12

sition to its operative drive position in said action zone comprises a spring anchored at one end to said wall element and at its other end to said actuator element and biasing said actuator element toward its operative drive position, said control member being moved by said stop dog against the yielding bias of said spring.

12. In a device of the class described, a supporting structure, an elongated track on said supporting structure, a carriage mounted on said track for movements longitudinally thereof, border strip engaging and supporting means on said carriage, drive means including a motor for imparting movement to said carriage selectively in opposite directions on said track to transport said border strip, and control mechanism for said drive means, said control mechanism comprising a control member extending longitudinally of said track and shiftable with respect thereto, a plurality of longitudinally spaced abutment elements on said control member, a stop dog mounted for common traveling movements with said carriage and for independent movements transversely thereof into and out of registration with said abutment elements, an actuator mounted in said frame structure for shifting movements selectively between an intermediate neutral station and forward and reverse action zones and movable in opposite directions in each of said action zones between operative drive positions and idle positions, said frame defining a wall element adjacent said actuator, a pair of laterally spaced fulcrum members on said wall element, said actuator defining laterally spaced surface portions each engageable with a different one of said fulcrum members for sliding and swinging movements relative thereto, each of said fulcrum members being engaged by a cooperating one of said surface portions to prevent movement of said actuator toward either operative drive position when said actuator is positioned at said neutral station, shifting of said actuator to either one of said action zones causing disengagement of one of said fulcrum members by its respective one of said surface portions to permit sliding and swinging movement of said actuator in one of said action zones about the other of said fulcrum members, linkage connecting said actuator to said control member, traveling movements of said carriage in either a forward or reverse direction being initiated by shifting of said actuator from its neutral station to the operative drive position in a selected one of said action zones, a pair of opposed springs anchored at one end to said wall element and at their other ends to spaced portions of said actuator and yielding urging said actuator toward engagement of said surface portions thereof with their respective fulcrum members, movement of said actuator from its neutral position toward one of said action zones causing one of said springs to approach a dead center relationship with the engaged one of said fulcrum elements, the other one of said springs causing swinging and sliding movement of said actuator about said engaged fulcrum element toward its operative drive position, engagement of one of said abutment elements by said stop dog during traveling movements of said carriage imparting limited movement to said control member to cause said actuator element to be moved from its operative position to its idle position against yielding bias of said other one of said springs to render said drive means inoperative, and means for moving said stop dog out of engagement with said one of the abutment elements to permit said other one of the springs to move said actuator to its operative drive position.
